Primary Examiner — Patricia Palasik(74) *Attorney, Agent, or Firm* — Hasse & Nesbitt LLC; W. Charles Ehlers; Daniel F. Nesbitt(57) **CLAIM**

I claim the ornamental design for a torch, as shown and described.

DESCRIPTION

FIG. 1 is a perspective view of the torch;

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings are for illustrative purposes only and form no part of the claimed design.
